UNITED STATES PATENT OFFICE.

JOHN B. POWELL, OF PHILADELPHIA, PENNSYLVANIA, ASSIGNOR TO DANIEL P. DIETRICH AND RICHARD M. POPHAM, BOTH OF SAME PLACE.

SPRING-MOTOR.

SPECIFICATION forming part of Letters Patent No. 367,234, dated July 26, 1887.

Application filed April 23, 1887. Serial No. 235,873. (No model.)

To all whom it may concern:

Be it known that I, JOHN B. POWELL, a citizen of the United States, and a resident of Philadelphia, Pennsylvania, have invented 5 certain Improvements in Spring-Motors, of which the following is a specification.

My invention relates to improvements in spring-motors of the class having a central arbor with a series of boxes containing sets of 10 springs.

The object of my invention is to make the device more compact than heretofore, to wind up the springs from the top down, and take the power from the bottom by means of a central shaft.

A further object is to have the boxes adjustable independently of each other, and to adjust the belt-wheel of the motor in respect to the belt-wheel of the machine to be driven, so that different speeds may be obtained from one belt, as fully described hereinafter.

In the accompanying drawings, Figure 1 is a sectional elevation of my improved spring-motor, on the line 1,2, Fig. 2. Fig. 2 is a plan view. Fig. 3 is a side view of the upper portion of the machine only; and Fig. 4 is a sectional plan on the line 3,4, Fig. 1. Fig. 5 is a detached perspective view of one of the details of the invention.

30 A is the base of the machine, A' is the top frame, and A² an intermediate frame. The frames A' A² are supported and secured together by vertical rods *a* and sleeves *a'* in the manner common to spring-motors of this class.

35 B is the central driving-shaft having its bearings in a cup, *b*, on the base A. Placed one above another over this shaft B are tubular arbors D D' D², the bottom, which supports the others, being itself supported on the 40 rim of the cup *b*.

E E' are the boxes containing the springs F, and each box is provided with two springs.

I have shown in Figure 1 only two boxes; but it will be understood that any number of 45 boxes may be used, as required. Each box is, in the present instance, constructed in three parts, the two cages *e* and *e'* and the open cap-plate *e²*. The portion *e* rests on a sleeve, *e*, adjustably secured to one of the arbors D' 50 or cup on the bottom plate, A, by means of a

set-screw, *c*. The cup or half-box *e'* fits in the cage or half-box *e*, as shown in Figs. 1 and 4, and the open cap-plate *e²* forms a cover to the half-box *e'*. All these parts *e e' e²* have suitable journals, through which pass the arbors D D', so that the boxes are thereby kept steady, while at the same time serving to support the arbors.

On the lower portion of each arbor is a reduced extension, *d*, which fits into a pocket, 55 so *d*, in the top of the arbor directly below it, as shown in Fig. 1, and the ends of the arbors are cut away to adapt them to the journals of the box *e'*. The exterior diameters of these journals are somewhat smaller than the 60 diameters of the arbors, which prevents any frictional contact between the springs F and the said journals. The inner end of each spring is secured to an arbor by a screw, *f*, as shown in Fig. 1, and the outer ends of the 65 springs are secured to the boxes, as shown in Fig. 4, by means of an upright pin, *f'*, passing through the shell of the box. The upper arbor, D², extends through the top frame, A', and to this arbor is secured a bevel gear-wheel, 70 G, having teeth *g*, which engage with two bevel-pinion, H H', on shafts *h h'*, having their bearings in extensions of the frame A'. These 75 shafts have squared ends, to which may be adapted any suitable handle for winding up 80 the springs.

On the periphery of the bevel gear-wheel G, and forming part of it, is a ratchet-wheel, I, and on the frame A' are pawls *i*, which engage with the ratchet-teeth on the wheel. The pawls 85 are pressed against the wheel by springs *i'*, as shown in Fig. 2.

I have placed the two shafts for winding up 90 the motor at right angles to each other, so that when the motor is applied to a sewing-machine the operator can wind the springs up by placing the crank-handle on the squared shaft *h* and wind the springs without leaving her seat at the machine, while if, at the same time, an attendant wishes to wind up the 95 machine, he can do so by placing the crank-handle on the shaft *h'* without disturbing the operator of the sewing-machine.

I have also provided the shaft *h* with a small bevel-pinion, H, and the shaft *h'* with a larger 100

bevel-pinion, H' , since a person standing at the side of the machine can exert more power than when sitting down. In fact, in order to wind the springs at all conveniently when 5 sitting down the pinion should be small.

The operation of winding will be considerably longer with the small pinion, while by using the large pinion at the side; although it takes more power, the speed is increased to a 10 great extent, as will be readily understood by referring to Fig. 2.

The central shaft, B , is secured to the lower arbor, D , and on the upper end of this shaft is secured a bevel driving-wheel, J , which 15 meshes with a bevel-pinion, J' , on a shaft, K , having its bearings on the top frame, A' , of the machine. At the outer end of this shaft K is a gear-wheel, k , Figs. 2 and 3, which gears with a small pinion, k' , on a shaft, K' . 20 On this shaft K' is a large gear-wheel, k^2 , gearing with a pinion, k^3 , on a stud projecting from an arm, L , pivoted to a bracket, L' , on the frame. This arm also carries a pinion, k^4 , which meshes with the pinion k^3 , 25 and is on one end of a shaft, M , having its bearings also in the arm L . On the opposite end of this shaft M are the driving belt wheels m m' , over which the belt of the machine to be driven is passed.

30 The train of gears above described is for increasing the speed from the gear-wheel J , which travels very slowly, to the shaft M , which is required to travel at an increased speed.

35 The arm L , as before remarked, is pivoted to the bracket L' , and is supported at its outer end by an extension, A^3 , of the frame. I have shown in the drawings this extension slotted for the reception of a bolt, l , which passes 40 through the arm L , and has a thumb-nut, l' , by which the arm L can be firmly secured to the extension A^3 .

In Fig. 3 of the drawings I have shown the belt-wheel W of an ordinary sewing-machine, 45 and a belt, w , which passes over the belt-wheel and over the wheel m on the shaft M .

It will be seen that by adjusting the arm L to or from the wheel W of the sewing machine any tension required can be placed upon the 50 belt w and the arm firmly secured to the upright A^3 by the nut l' ; but if the speed of the sewing-machine is to be decreased the belt is placed on the smaller wheel, m' , and the arm loosened from the upright A^3 , and 55 by pressing the arm downward, Fig. 3, the belt will be tightened and all the slack taken up. Then by securing the arm to the upright A^3 by the nut it may be held firmly in place. It will be noticed that when this arm 60 L , with its shaft M , is moved from one position

to another, the pinion k^3 and gear-wheel k^2 always remain in gear with each other, owing to the arm being pivoted on the axial line of the gear-wheel k^3 .

On the inner end of the shaft K' is a brake-drum, N , on which the brake-shoe N' rests. This brake-shoe is pivoted to a stud, n , on an extension of the frame A' , as shown in Fig. 2. The outer end of this brake-shoe N' is forced down on the drum N by a spring, n' , and is 70 raised by a cord, n^2 , connected to any suitable device—such as a treadle—for raising the shoe clear of the drum when required.

I claim as my invention—

1. The combination, in a spring-motor, of 75 the frame containing the spring-boxes and springs with a set of arbors, of which the upper one is connected to the winding mechanism, and a central driven shaft, B , to which the lower arbor is secured, substantially as set forth.

2. The combination, in a spring-motor, of 80 the central arbors, with boxes E , carrying springs F , one end of each spring being connected to the box and the other end to the arbor, with adjustable sleeves c , supporting the boxes, substantially as set forth.

3. The combination, in a spring-motor, of 85 the driving mechanism, and an arm, L , carrying belt-pulleys m m' , with a driven pulley and a belt, and devices for adjusting the belt-pulleys m m' to and from the driven belt-pulley, substantially as set forth.

4. The combination, in a spring-motor, of 90 the springs and their boxes and the driven shaft, with speeding-gears, a gear, k^2 , and an arm, L , carrying the gears engaging with the wheel k^2 , and a shaft, M , having at one end a pinion, k^4 , geared with the wheel k^2 , and at the opposite end pulleys m m' , and adjusting mechanism by which the arms can be secured in any position, substantially as set forth.

5. The combination, in an upright spring-motor, of the winding bevel gear-wheel G , secured to one of the upright arbors of the motor, with two shafts, h h' , having bevel-pinions gearing into the wheel G , whereby the motor can be wound from two points, substantially as specified. 105

6. The combination, in a spring-motor, of 110 the winding gear-wheel G with shafts h h' , having pinions of different sizes gearing with the wheel G , substantially as set forth.

In testimony whereof I have signed my name to this specification in the presence of two subscribing witnesses. 115

JOHN B. POWELL.
